COLLAR

Edward Lind and David Feigenbaum,
New York, N. Y.

Application January 30, 1933, Serial No. 654,212

2 Claims. (Cl. 2—132)

This invention relates to improvements in apparel collars and more particularly to collars of the soft turnover type commonly used in combination with men's shirts of the negligee type either as a separate element or permanently attached thereto.

Heretofore some collars of the soft turned-down type have been provided in their front folds with pockets adjacent the front edges thereof to hold stiffening members to prevent curling or wrinkling, while others have been provided with tabs or the like to prevent the spreading of the meeting edges of the front folds of the collars. To derive the benefits of both these instrumentalities and to combine the same, in a cheap, economical, practical and efficient manner is the primary and principal object of this invention. It is impractical, cumbersome and uneconomical to apply the present day means for the simultaneous enjoyment of both these features.

An object of the invention resides in the provision of combined means in a practical, commercial, economical and convenient form for maintaining the front portions of the folded-over element of a soft collar, firm, unwrinkled and uncurled and for preventing the spreading of the meeting edges of the folded-over element.

A further object of the invention resides in the provision of members which when folded and seamed to the front portions of the folded-over top of a collar will present pockets receptive of stiffening means to maintain the collar in up-standing position and buttonholed tabs to facilitate the collar being snugly fitted around the knot of the tie.

A further object of the invention is to provide in a soft collar a combined pocket forming element and tab preferably formed from a single blank, and located adjacent each front edge of the collar, the pockets being adapted to receive stiffening members to maintain the front portions of the collar firm and unwrinkled, the tabs being adapted to cooperate, when properly adjusted, to keep the meeting edges of the collar from spreading thereby comfortably positioning the collar on the person and presenting a neat appearance.

These and other objects of the invention and the means for their attainment will be more apparent from the following detailed description taken in connection with the accompanying drawing, illustrating an embodiment of which the invention may be realized and in which:

Fig. 1 is a perspective view of the top part of

a shirt with collar attached embodying and employing the invention.

Fig. 2 is a partial elevational view of the same with the front portion opened and the collar turned up. 5

Fig. 3 is a plan view of a blank by which an embodiment of the invention may be realized.

Fig. 4 is a bottom view of the blank with the edges folded in.

Fig. 5 is a view of the folded-in blank doubled over or folded upon itself. 10

Fig. 6 is a sectional view taken along the line 6—6 of Figure 2 and looking in the direction of the arrows.

Fig. 7 is a sectional view taken along line 7—7 15 of Figure 2 and looking in the direction of the arrows.

The drawing shows the invention in one of its practical forms.

Referring to the drawing, the numeral 10 represents the band provided with the conventional buttonholes 11 adjacent the front edges and near the lower ends thereof. The numeral 12 represents the folded-over top of the collar joined to the band 10 in the conventional manner. The 25 band is shown in the drawing as being further provided with a top button 13 and a top button-hole 14, adapted to cooperate with the top button 13 to prevent the overlapping front edges from spreading after the band is adjusted on the 30 wearer.

The collar may be of the separate type or may be permanently attached to the shirt. The drawing shows the band 10 sewed on a shirt 15 in the customary manner. The folded-over top 12 of 35 the collar is preferably formed of three plies of soft fabric comprising an inner or bottom ply 16, an outer or top ply 17 and an intermediary or interlining ply 18 which are, in the conventional making of the folded-over top, superposed one 40 upon the other with the bottom ply 16 and intermediary ply 18 outermost and united together by a line of stitching 19.

In the customary making of the collar the plies are turned inside out between the bottom and top plies 16 and 17, respectively, by which the line of stitching 19 is concealed and the plies are closely held together at spaced distances from the edges of the plies by a marginal line of stitching 20. 45

In an embodiment of the invention combined pockets and tab forming members are employed which are shown as blanks 21 cut or stamped to form opposed outwardly projecting arcuate tab portions 22 and aligned extensions 23 and 24. 50 55

As shown in Fig. 4, edges 25 of the blank are folded in, and the blank is then doubled over or folded upon itself as shown in Fig. 5, with the tab portions 22 in register. The end of the folded-over extension 24 is preferably made angular as shown at 26, and the end of folded-over extension 23 may also be made angular as shown at 27. A buttonhole 28 is formed in the registered tab portions 22. The edge of the folded-over blank 21 at the tab portion and adjacent thereto is stitched as shown at 29.

Before the plies of the folded-over top 12 of the collar are assembled, the combined pocket forming and tab members 30 formed from the blank 21 are united to the inner or bottom ply 16 near each end thereof by the rows of stitches 31, 31'. The plies are then assembled in the manner hereinbefore stated, and the whole united by means of the line of stitching 19. The plies forming the folded-over top 12 are then turned inside out as previously stated and the marginal line of stitching 20 run, and the said top is attached to the band 10 in the conventional manner. The pockets 34 formed by the now vertical portions of members 30 and the inner ply 16 are adapted to receive stiffening members 35 for the purpose of maintaining the front edges of the folded-over top in a firm, unwrinkled and uncured condition. The members 30 extend up from the lower edge of the folded-over top 12 and need not extend to the upper edge of the folded-over top only sufficient length being required as to support the stiffening members in position. The end portions of the tabs 25 extend beyond the ends of the top 12.

The stiffening members should be slightly longer than the depth of the pockets to facilitate their being easily removed. However, by making the upper end or edges of the member 30 angular as indicated at 26, the stay or stiffening member may be of the same lengths as the depth of the pocket, sufficient thereof being exposed by virtue of the shape of the upper end of member 30 to permit its easy withdrawal.

By constructing a collar in accordance with our invention, we have provided pockets in the frontal portions thereof for the purpose of confining and retaining the stiffening members, and also tabs having the buttonholes 28 adapted to register with the buttonholes 11 when the collar is in position, all of said buttonholes being able to receive the shank of the same collar button. Although it is preferable to have the stay retaining pocket formed between the inner ply 16 and member 30, since the latter is formed by doubling the blank over itself, the space therebetween may be utilized for the pocket.

To adjust the collar, the buttonholes 11 are made to engage the shank of the collar button 60 and the tie 37 is positioned between the band 10

and folded-over top 12. The tie is then knotted in the usual manner and the tabs of members 30 made to engage the shank of the collar button under the tie. The knot of the tie will be held in adjusted position with the ends of the folded-over top held down close to the neck-band, the ends of the folded-over top being prevented from spreading.

As seen in Figs. 3, 4 and 5, the substantially cross-shaped member or blank 21 is folded upon itself to comprise the substantially T-shaped combined pocket forming and tab element 38.

It is preferable to have the blanks 21 made of the same material as the collar, so that the protruding portions of the member formed from the blank may conform with the collar material. Heretofore in making pockets for receiving stiffening members, the same were formed usually from white tape which would show a decided contrast to the collar in the event the latter was made from colored or striped material.

In the accompanying drawing we have illustrated the invention embodied in one of its practical commercial forms but as this illustration is primarily for purposes of disclosure it will be understood that the invention is not limited to this particular form of structure and that it may be modified in many respects without departure from the true spirit and scope of the invention as herein defined and claimed. We wish it further understood that the terms which we have employed herein are used in a descriptive rather than in a limiting sense, except however for such limitations that may be imposed by the state of the prior art.

Having thus described our invention, what we claim as new and desire to secure by Letters Patent, is:

1. A collar comprising a neckband and a turned-down portion, and a combined buttonhole tab and pocket-forming element attached to the said turned-down portion adjacent the meeting edges thereof, said combined tab and pocket-forming element comprising a substantially cross-shaped single blank folded upon itself to produce a T-shaped member the head of which becomes the pocket and the leg of which becomes the buttonhole tab.

2. In a collar having a neckband and a turned-down portion, the turned-down portion being provided with a combined buttonhole tab and pocket-forming part located in the vicinity of its ends, said combined tab and pocket-forming part comprising a substantially cross-shaped single blank folded upon itself to produce a T-shaped member, the head of which becomes the pocket and the leg of which becomes the buttonhole tab.
